BLOWTORCH

David Allen Lenk, Newton, Mass., assignor to
Samuel C. Brody, Brookline, Mass.

Application December 21, 1933, Serial No. 703,430

13 Claims. (Cl. 158—35)

This invention relates to blow torches.

Considerable difficulty is experienced in keeping blow torches continuously operating, both those having a Bunsen burner and those requiring a constant priming flame. This difficulty is due to a charring of the wick in the pressure generating tube, as a result of the excessive heat at the outside end with the result that the torch will not burn properly or is extinguished. To overcome this the end of the wick has been set back from the outside end of the pressure generating tube; but oftentimes handling of the torch causes the wick to move from the position it was placed in. One object of my invention has been to provide a means which would hold the wick in a predetermined position in the pressure generating tube and which will positively prevent it from moving to the outside end of said tube where it would soon be charred.

When the torch is turned upside down a rush of liquid into the pressure generating tube will extinguish the torch, and several expedients such as plugs in the reservoir have been used to prevent this; but the plug does not compress the wick, and being a light object it does not stay in a desired position. To remedy this I do away with the plug entirely and tie a knot in the wick at the entrance to the pressure generating tube which is large enough to prevent any rush of fuel into said tube; but always permitting the gradual passage of fuel by capillary attraction.

The foregoing and other objects which will appear as the nature of the invention is better understood, may be accomplished by a construction, combination and arrangement of parts such as is disclosed by the drawing. The nature of the invention is such as to render it susceptible to various changes and modifications, and, therefore, I am not to be limited to the construction disclosed by the drawing; but am entitled to all such changes therefrom as fall within the scope of my claims.

In the drawing:

Figure 1 is a side elevation of my blow torch. Figure 2 is a longitudinal section of my blow torch to illustrate the interior of the fuel reservoir and pressure generating tube.

Figure 3 is an enlarged longitudinal section broken away to more fully illustrate the position of the conical spring and wicking in the pressure generating tube.

My invention is applicable to all types of blow torches, and I have illustrated one with a fuel reservoir 12 to hold a vapor forming fuel such

as denatured or grain alcohol or gasoline, having a handle 13 and a removable top section 14, to which is united a pressure generating tube 15, oftentimes called a gooseneck tube, which extends part way down into the reservoir 12, as illustrated in Figure 2 of the drawing. Said reservoir may be made as a unit, and filled at the bottom. A combustion burner tube 16 is shown, commonly called a Bunsen burner, which has a nut-like portion at its inner end that screws onto said pressure generating tube 15, to connect the two. The usual air control nut or ring 18 is screw threadedly mounted on said combustion burner tube 15. This invention is equally adaptable to torches which require continuous priming and do not have a Bunsen burner.

A hollow metal jet plug 19, which is closed at one end, is screwed into the outside end of the pressure generating tube 15, which plug has a jet orifice 20 drilled in said closed end, of a diameter of .013 or thereabouts.

Within said fuel reservoir 12 is wicking 22 which extends from the bottom thereof up into the pressure generating tube 15; but not to the outer end thereof, as it is intended that a definite space shall be left in said pressure generating tube 15 between its outer end and the end of said wicking 22. Said wicking is tied in a knot 23 at the entrance to the pressure generating tube 15 to thereby compress it and retard the flow of fuel. This knot will not prevent fuel working its way through it gradually, but will prevent a rush of fuel into said tube 15 when it is upside down, which would extinguish the torch.

In order to definitely hold said wicking 23 spaced away from the outside end of said pressure generating tube 15, and thereby avoid charring of the wicking, I insert a member which is shown in the form of a conical spring 24, which is made of some suitable metal such as copper, bronze, et cetera but may be made of a combination of metal and other material. This spring 24 tapers in diameter towards the outside end, which smaller outside end fits into the hollow portion of said jet plug 19. Inasmuch as the inside diameter of part of said spring 24 is less than the thickness of said wicking 22, as best illustrated in Figure 3 of the drawing, the wicking cannot possibly move to the end of the pressure generating tube where it would get charred. This also eliminates any possibility of plugging of said orifice 20. Said wicking 22 enters the large end of said spring 24 and extends therein as far as it will go where it is held, so that said wicking remains at a predetermined point in the pressure gener-

ating tube, regardless of what position my blow torch is in. The expandible positioning member, when made of heat conducting material, serves as a heat conductor and intensifier to carry the maximum heat back along its entire length and for a substantial distance down into the wick tube, thereby vaporizing and volatilizing the gases from the liquid fuel with which the wick is saturated. This has the effect of creating far greater gas pressure than has heretofore been possible and hence of producing a much stronger and intense blast flame. It also enables the wick to be positioned within the wick tube with its outer end spaced a substantial distance away from the outer end of the wick tube so that flame from the priming pan, or other flame source, cannot char the wick and cause the torch to become inoperative.

The space within which the positioning member is located is, of course, devoid of wick, and may therefore serve as a gas expansion space. The presence of the positioning member, when made of heat conducting material, within said space creates the maximum heating effect on the already-volatilized gases within said space, thereby producing maximum gas pressure. This space, when so filled with gas, also excludes the entrance of air, thus furthering the emission of a steady stream of clear, volatilized gases.

The wick itself, when co-acting with the positioning member, may be used to adjustably expand the positioning member either longitudinally or transversely along or against the inner face of the wick tube wall.

While I have shown the wick tube as of conventional "gooseneck" shape, it will be understood that my invention is not limited to this or any other shape of wick tube. It will also be understood that the wick positioning member if desired may be made longer or shorter than is illustrated in the drawing and may or may not extend into the jet plug.

What I claim is:

1. In a blow torch, in combination, a fuel reservoir, a pressure generating tube communicating therewith, a wick in said reservoir and tube, and a resilient member in said tube to keep said wick spaced away from the outside end of said tube.

2. In a blow torch, in combination, a fuel reservoir, a pressure generating tube communicating therewith, a wick in said reservoir and extending part way into said tube, and a spring in said tube to keep said wick spaced away from the outside end of said tube.

3. In a blow torch, in combination, a fuel reservoir, a pressure generating tube communicating therewith, a wick in said reservoir and extending part way into said tube, and a conical spring in said tube extending in front of said wick to keep said wick spaced away from the outside end of said tube, said spring tapering in diameter towards said outside end.

4. In a blow torch, in combination, a fuel reservoir, a pressure generating tube communicating therewith, a wick in said reservoir and tube, a jet plug in the outside end of said tube, and a conical spring in said tube to keep said wick spaced away from the outside end of said tube, said spring tapering in diameter towards said outside end, the small end of said spring entering said plug, said wick entering the large end of said spring and extending therein part of the length of said spring, the inside diameter of a

portion of said spring being less than the thickness of said wick.

5. In a blow torch, in combination, a fuel reservoir, a pressure generating tube communicating therewith, a wick in said reservoir and tube, a jet plug connected to and entering the inside of said tube, said jet plug having an opening therein which communicates with and is smaller than the opening in said tube, and a member having a large end and a small end, extending at its small end into the said opening in said jet plug and extending at its large end into said tube, said wick entering and extending into said large end of said member.

6. In a blow torch, a fuel reservoir, a pressure generating tube communicating therewith, a wick in said reservoir and tube, and means frictionally engaging both the inner face of said tube and the wick for positioning said wick in pre-determined spaced relation to the outside end of said tube.

7. In a blow torch, a fuel reservoir, a pressure generating tube communicating therewith, a wick in said reservoir and tube, a jet plug in the outside end of said tube, there being a space between the outer end of the wick and the jet plug, and a member located in said space and extending into said plug at one end and at its other end frictionally engaging both the inner face of said tube and the wick for positioning said wick in pre-determined spaced relation to said jet plug.

8. In a blow torch, a fuel reservoir, a pressure generating tube communicating therewith, a wick in said reservoir and tube, a jet plug in the outside end of said tube, there being a space between the outer end of the wick and the jet plug, and a member located in said space and extending into said plug at one end, the wick extending part way into the other end of said member and being frictionally retained thereby, and said member having a portion frictionally engaging the inner face of said tube for positioning said wick in pre-determined spaced relation to said jet plug.

9. In a blow torch, a fuel reservoir, a pressure generating tube communicating therewith, a wick in said reservoir and tube and terminating a distance from the outer end of said tube, and an expandible positioning member frictionally engaged against the wall of the wick tube for adjustably supporting the outer end of the wick in desired position within the tube, said wick being frictionally locked with the inner end of said positioning member.

10. In a blow torch, a fuel reservoir, a pressure generating tube communicating therewith, a wick in said reservoir and tube and terminating a distance from the outer end of said tube, and an expandible positioning member frictionally engaged against the wall of the wick tube for adjustably supporting the outer end of the wick in desired position within the tube, the outer end of the wick being engageable with the inner end of the positioning member.

11. A blow torch as claimed in claim 9 wherein said positioning member is of heat conducting material to serve as a heat conductor and intensifier which carries the heat a substantial distance back of the outer end of the wick tube.

12. A blow torch, comprising a wick tube having a jet opening adjacent its outer end and a wick in said tube, there being a space between the outer end of the wick and the jet opening, and a wick positioning device frictionally lodged

within said space and constrictively engaging the wick adjacent the outer end thereof.

13. A blow torch, comprising a wick tube having a closed outer end provided with a jet orifice, a wick in said tube, there being a space between the outer end of the wick and the jet orifice, and

a wick positioning device within said space, said device being re-active at one end against the outer end of the wick and being re-active at its other end against the outer end of the wick tube.
